UNITED STATES PATENT OFFICE.

DOLLETTA M. ACKERMAN, OF LONG BEACH, CALIFORNIA.

MASSAGE APPLICATOR.

Application filed May 11, 1925. Serial No. 29,289.

My invention aims to provide an improved message applicator particularly adapted to be applied to the human body, when connected to a source of vacuum such as an aspirator.

5 In the accompanying drawing, wherein I have shown two illustrative embodiments of my invention;

Fig. 1 is a side elevation of my improved applicator, the manner of use by connection 10 to an aspirator being indicated in dotted lines;

Fig. 2 is a central sectional view taken on the line 2—2 of Fig. 1;

Fig. 3 is a central sectional view taken on 15 the plane at a right angle to the plane 2—2 in Fig. 1; and

Fig. 4 is a cross-sectional view of a modified form of applicator.

Referring to the drawings, and more particularly to the illustrative embodiment shown in Figs. 1 and 2, I have shown one form of my improved suction massage applicator as being connected to an aspirator which creates the necessary suction. This 25 cup preferably comprises a body portion 10 of soft material such as rubber, shown as being bell-shaped, and having its wall tapered toward the flared edge to insure the desired flexibility so that, by gentle pressure, it may 30 be made to conform to the irregular contour of portions of the body. The thicker portions of the walls are sufficiently strong to resist collapse due to the application of the suction.

35 At the rear of the cup I have shown a beaded enlargement 11 which forms a convenient means for holding it, also provides a thickened portion in which an annular channel 12 is formed to receive a tubular fitting or nipple 40 13, preferably made of metal. This nipple may have an annular shoulder 14 slightly larger in diameter than the normal internal diameter of the annular channel, so that when it is inserted through the mouth of the cup 45 by expanding the throat portion, it will be held firmly in air-tight engagement therewith. The nipple portion projecting from the throat of the cup is preferably roughened to engage the interior of a rubber tube such as 50 is usually employed in connection with suction massage devices.

Referring to Fig. 3, I have a valve 15 adapted to slide over and close the opening in the nipple to cut off suction. As shown, this 55 valve preferably has an integral boss 16 provided with a threaded opening to receive a

threaded stem 17 which is inserted through a small opening in the beaded portion 11 of the cup. This stem preferably has a knob 18 on its projecting end, and a coil spring 19 may 60 be inserted between the knob and the bead 11 normally to hold the valve open.

It is desirable to provide for releasing the cup from the body without bruising the flesh and to this end I have shown an opening 20 65 in the wall of the cup adapted to be covered by a finger of the user when it is being applied, and to be uncovered to permit air to replace the partial vacuum in the cup when it is desired to remove it. The wall of the 70 cup is preferably thickened around the opening to strengthen and to provide a hump or boss on the outer surface which makes it easy for the operator to locate the opening by the sense of touch.

Referring to Fig. 4 I have shown a cup 10' 75 of smaller size than the one hereinbefore described and preferably made of hard material such as glass. This cup preferably has an integral nipple 13' adapted to be inserted 80 in the usual rubber tube and the mouth is of such size that it may be applied to the face for removing wrinkles, cleansing the pores of the skin or removing pimples and the like. I have also shown an opening 20' to admit 85 air in this cup when it is desired to release it.

In the practical application of my flexible massage cup cold cream or olive oil are preferably applied to the parts of the body which it is desired to massage so as to make it easy 90 to move the massage cup about over the skin without causing irritation from friction. The operator then applies the cup, holding one finger over the air opening and moves it about over the body. To remove the cup, the 95 operator closes the valve by pushing the knob 18 with one finger and uncovers the opening 20 in the side wall to admit atmospheric air, thereby destroying the vacuum.

The facial massage cup is applied in a similar manner, the air opening 20' in this cup being sufficiently large to admit atmospheric air in such volume as to permit easy release 100 without injury to the skin.

This applicator not only cleanses the pores 105 of the skin on these portions of the body where it is applied, but also contributes to better blood circulation and by repeated application will reduce fat partly due to the vigorous artificial exercise afforded and partly 110 to the removal of some of the fatty oils through the pores of the skin.

Obviously, my invention is susceptible of various changes and uses.

I claim:

1. A massage applicator comprising a flexible bell shaped rubber cup having a thin edge at its open end and a tube engaging nipple secured in its rear end, said nipple presenting an annular shoulder and said cup having an annular channel for receiving said shoulder in air-tight engagement therewith, and said cup having an opening in the side thereof, whereby the vacuum in the cup is controlled.
2. A massage applicator comprising a flexible bell-shaped rubber cup, having a thin

edge at its open end, a tube engaging nipple secured to the rear end thereof, said nipple including an annular plate shoulder, said cup having an annular channel for receiving said plate in air-tight engagement therewith, a hand grasping portion at the rear end of said cup, said cup having an air opening in the side thereof adapted and arranged to be covered by a finger of the user, the walls around said opening being thickened and presenting a hump on the exterior surface to facilitate finding said opening by the sense of touch.

In witness whereof I this day set my hand.

DOLLETTA M. ACKERMAN.
